UNITED STATES PATENT OFFICE.

SCOTT H. HULL, OF OSKALOOSA, IOWA.

DESIGN FOR A CHECKREIN GUIDE-LOOP.

SPECIFICATION forming part of Design No. 26,793, dated March 23, 1897.

Application filed January 30, 1897. Serial No. 621,364. Term of patent 14 years.

To all whom it may concern:

Be it known that I, SCOTT H. HULL, a citizen of the United States, residing at Oskaloosa, in the county of Mahaska and State of Iowa, have invented and produced a new and original Design for a Checkrein Guide-Loop; and I do hereby declare the following to be a full, clear, and exact description of the same, reference being had to the accompanying drawings, forming a part thereof.

My invention has relation to a new and useful design for a checkrein guide-loop for harness.

It relates to the entire configuration of the loop.

My invention relates particularly to the loop as illustrated in the accompanying drawings, in which—

Figure 1 is a perspective view of a checkrein-loop embodying my design. Fig. 2 is a longitudinal section of the same.

The leading features of my design appear in the following description.

1 represents the base or body of the loop, and 2 2 the upwardly and inwardly curved arms.

3 represents the tubular shank or rivet, formed with a beveled edge 4.

Having thus fully described my invention, what I claim as new and useful, and desire to secure by Letters Patent of the United States, is—

The design for a harness-loop, substantially as herein shown and described.

In testimony whereof I affix my signature in presence of two witnesses.

SCOTT H. HULL.
